BED-RECIPROCATING MECHANISM.

1,269,210.

Specification of Letters Patent. Patented June 11, 1918.

Original application filed May 12, 1915, Serial No. 27,506. Divided and this application filed August 22, 1916. Serial No. 116,362.

To all whom it may concern:

Be it known that we, HERBERT PEARCE and FRED SPENCE, subjects of the King of the United Kingdom of Great Britain and Ireland, and residing at Linotype and Machinery Works, Broadheath, in the county of Chester, England, have invented new and useful Improvements in Bed-Reciprocating Mechanism, of which the following is a specification.

This invention relates to bed-reciprocating mechanism of the class described in our prior application for Letters Patent Serial Number 27506 filed May 12th 1915 (hereinafter termed the original application), from which the present application is a division. It is especially adapted for use in connection with, and is hereinafter dealt with as applied to, the beds of flat-bed printing presses, although it is to be understood that the invention may equally well be employed in connection with the reciprocation of the beds of planing and similar machines.

To secure the best results in a flat bed printing press, it is necessary that the bed travel through its printing and return strokes at a uniform velocity and that, at the end of these strokes, and with as little strain as possible, the bed be brought gradually to a stop and have its direction of travel reversed and its velocity in the reverse direction gradually accelerated from the stop or zero up to the maximum. It is also of very great importance that for the slowing down, stopping and reversal of the bed, as small a proportion as possible of the bed's total travel be utilized, because the smaller that proportion, the greater will be the proportion available for printing, and consequently the greater will be the length (measured in the direction of the bed's travel) of the surface which can be printed at each cycle of the press.

In the above-mentioned original application there is described a reversing device comprising a single crank pin to which are pivoted the meeting ends of two connecting rods whose outer or opposite ends are pivotally connected each to a slide rectilinearly reciprocated by the crank pin in a direction parallel with the movement of the bed; and devices including a single automatically op-

erated latch for connecting the bed to, and disconnecting it from, the said slides in alternation near respectively opposite ends of the bed's travel, the arrangement being such that the control of the bed is transferred from the normal bed-operating gear which operates the bed at uniform velocity during the actual printing stroke and the return stroke, to the crank pin, and again from the crank-pin to the normal bed-operating gear, at opposite ends of the travel of the bed.

This arrangement was designed so as to effect each complete reversal within a period less than one half of that occupied by one rotation of the crank, and thereby to extend the travel of the bed at uniform velocity beyond the period occupied by one complete rotation of the bed driving pinion, and it was shown to be essential, for this purpose, to have the connecting rods and crank of such relative lengths that, when the velocity of the respective slide in the direction of the bed's travel is approximately equal to that of the bed, the equation

$$L = \frac{r \cos a}{\sin b}$$

is satisfied, where L represents the length of the connecting rod, r the radius of the crank arm, a and b the angles formed by the crank radius and connecting rod respectively with vertical and horizontal lines passing through the axis of rotation of the crank, and

$$\tan b = \frac{180}{\pi(180+a)}$$

a defining a position of the crank when the velocity of the slide is at or decreasing from its maximum.

The just-named conditions, however, are applicable only to constructions in which both connecting rods are of the same length and in which the travel of the bed in one direction at uniform velocity would, if the reversal were carried out according to previously known arrangements, extend over a period occupied by not more than one complete rotation of the bed driving pinion.

The object of the present invention is to secure results similar to that attained by the

subject-matter of the original application, but without the limitations just referred to. Consequently, although the invention is hereinafter for convenience described and 5 illustrated in connection with a machine of the same general construction as that dealt with in the original application, such description and illustration is not to be regarded in any restrictive sense.

10 The invention will now be described by reference to the accompanying drawings, in which:—

Figure 1 is a diagrammatic side elevation of certain organs of a flat-bed printing press 15 of the above-named construction, and

Fig. 2 a diagram illustrating the principle governing the relative lengths of the crank and connecting rods according to the present invention.

20 1 is the bed motion shaft; 4, the bed pinion which, through the rack 12, serves to propel the bed 11 at uniform velocity during the printing stroke, and which is in constant driving connection with the said shaft, and 25 18, the bed pinion which, through the rack 20, serves to propel the bed 11 at uniform velocity during the return or non-printing stroke, and which may be co-axial with the shaft 1 and rotated by suitable gearing at 30 the same angular velocity as, but in the opposite direction to the said shaft, as indicated by arrows in Fig. 1.

The crank pin 30 is rigidly connected by a suitable crank, to the shaft 1, and has 35 pivoted on it the meeting ends of the two connecting rods or links 31, 32. The outer end of the rods 31, 32, are pivoted upon the studs or pins 33, 34, respectively, each of which is integral with, or fast to, the 40 block or slide 35, 36, which is capable of sliding in stationary horizontal guides (not shown in the drawings) in a direction parallel with the movement of the bed 11. Each of the slides 35, 36, is provided with 45 a device A, A', or B, B', herein termed a two-member hook as, although the members, A, A', and B, B', of the respective hooks are shown in the drawing at a distance apart, they are rigidly connected together by the 50 respective slide 35 or 36, and can be regarded as the equivalent of the corresponding hooks described in the original application. The members A', B', are situated in relatively opposite positions, that is to 55 say at the outer ends of the members A, B, relatively to the bed motion shaft 1.

To the underside of the bed 11, at or about the center of its length and movable between the two pinions 4, 18, and transversely to their common axis, there is rigidly secured the bracket or hanger 38, to which is rigidly secured the reversing stud 39 which is capable of engaging with the inner vertical faces of the aforesaid members A', B', when the control of the bed 11

has to be transferred from the pinions 4, 18, to the crank pin 30, that is to say, at those instants at which the reversing stud 39 and the members A', B', are traveling at equal velocity. On the hanger 38 there are provided two latches 40, 40^a, which may be curvilinearly movable as is the single latch in the original application, or rectilinearly movable in guides 51 as shown in Fig. 1, and which are respectively adapted to embrace the member A on the slide 35 and the member B on the slide 36 in such manner as to insure the bed 11 moving as if in one piece with the particular member A or B with which the respective latch is for the 80 time being engaged.

Each latch 40, 40^a, is provided with an anti-friction roller 41, 41^a, which engages with a respective cam race 42 or 43 at or near the respective end of the bed's travel so as, 85 at the required times, to move the respective latch into and out of engagement with the member A or B. Each latch 40, 40^a, is acted upon by a spring (not shown in the drawing) which maintains it in its higher position against a stop 46 during the time at which it is not under the control of its respective cam race 42 or 43. As both of the rollers 41, 41^a, project laterally from the hanger 38 to the same extent, and it is the 95 inner of the two latches 40, 40^a, which engages with the slide at respectively opposite ends of the travel of the bed, the two cam races 42, 43, are located at respectively different levels so that each cam race will 100 engage only the respective roller and allow the other roller to pass above or below it, thus, in the example illustrated, the roller 41^a of the latch 40^a passes unobstructedly over the cam race 42 and is engaged by the 105 cam race 43, and the roller 41 of the latch 40 passes unobstructedly under the cam race 43 and is engaged by the cam race 42. To prevent any damage being caused by reason of failure of the respective spring to 110 maintain a latch 40 or 40^a in its highest position against a stop 46, a ramp 50 is provided on the inner end of each cam race, such ramp serving to guide the respective roller 41, 41^a, into the higher portions of the 115 respective cam race 42 or 43.

The operation of the reversing mechanism according to the present invention may be described as follows, assuming, as a convenient stage from which to start such description, that the bed 11 has reached that part of its non-printing stroke at which the control of the bed is transferred from the pinion 18 to the crank pin. At that instant the position of the parts is as indicated diagrammatically in the drawings. The bed 11 and slide 35 are then traveling in the same direction at the same speed, the pinion 18 is just running out of mesh with the rack 20, and the reversing stud 39 and latch 40 130

have just come into engagement with the two members A', A respectively of the hook on the slide 35. The slowing down, stopping, starting on the printing stroke, and speeding up of the bed 11 take place during the next say $180-2a$ degrees of angular motion of the crank pin 30 (a being an angle hereinafter more particularly referred to), the bed traveling in rigid connection with the slide 35, and at any part of the time occupied by this angular movement of the crank pin, the bed pinions 4 and 18 are, by suitable means moved laterally to bring the former (4) into a position in which it will 10 subsequently be engaged by the rack 12 during the next ensuing or already started printing stroke, and the latter (18) out of the path which will be pursued by the rack 20 during that stroke. At the conclusion of 15 the just-mentioned $180-2a$ degrees angular motion of the crank pin 30 the slide 35 and bed 11 have again attained the velocity of the uniform travel of the latter, and the bed pinion 4 runs into mesh with the rack 20. Immediately thereafter the latch 40 is 25 moved rectilinearly in the guides 51, by the action of the cam race 42 on its roller 41, out of engagement with the hook-member A, and the stud 39 also moves out of contact 30 with the hook member A' by reason of the now slower movement of the latter, and the bed 11 continues its printing stroke under the sole control of the pinion 4 and rack 12, the latch 40, when it has run beyond the 35 control of the cam race 42, being meanwhile maintained by its spring in its raised position against the respective stop 46.

As the bed 11 approaches the end of its printing stroke, that is to say, at or about 40 the instant at which the pinion 4 completes the next $360+2a$ degrees of angular motion, the bed rack 12 runs out of mesh with the pinion 4, and the slide 36 is traveling at the same velocity as the bed. At or about that 45 instant the reversing stud 39 abuts against the hook-member B' on the slide 36 and the roller 41^a of the latch 40^a, which had by that time already been depressed by passing along the descending portion of the cam race 43, completes the engagement of that latch with the hook B, B', thus, for the time being, locking the bed 11 to, and placing it under the control of the crank pin 30. The 50 slowing down, stopping, reversing and speeding up of the bed now take place during the next ensuing angular motion of say $180-2a$ degrees of the crank pin 30, just as though the said crank pin were in permanent operative connection with that bed, and at any part of the time occupied by the 55 just-named angular movement of the crank pin, the bed pinions 18 and 4, are again moved laterally, to bring the former (18) into a position in which it will subsequently 60 be engaged by the rack 20 during the next 65 ensuing or already started non-printing stroke, and the latter (4) out of the path which will be pursued by the rack 12 during that stroke. At the completion of the just-mentioned angular motion of $180-2a$ degrees of the crank pin 30, the hook B, B', is again traveling at the same velocity as is the bed 11. At that juncture the bed rack 20 runs into mesh with and is operatively engaged by the pinion 18, and the mutual 70 separation of the stud 39, hook B, B', and latch 40^a commences, the latch being raised clear of the hook B, B', by the ascending part of the cam race 43, in the same manner as the latch 40 was previously raised by the 80 cam race 42 at the commencement of the printing stroke.

The bed 11 is then traversed through its non-printing stroke at uniform velocity by the rack 20 and pinion 18, and at or about 85 the instant at which the pinion 18 completes say $360+2a$ degrees of angular motion from the position at which the bed started the portion of its non-printing stroke of uniform velocity, the parts again assume the 90 position indicated in Fig. 1.

The use of two latches separated by an interval of distance, in accordance with the present invention, for effecting the reversal at respectively opposite ends of the bed's 95 travel, instead of, as in the original application, a single latch for effecting the reversal at both ends of the bed's travel, allows a considerable variation of the lengths of the connecting rods as compared 100 with those in the last-mentioned arrangement, and eliminates as a factor determining such length, the length of travel of the bed at uniform velocity.

In the present case, the length of the two 105 connecting rods can be of any predetermined value, provided that the conditions hereinafter set forth are satisfied, and not necessarily of equal values, these latter depending upon the distance at which the respective latches are, in the direction of travel of the bed, spaced from the mid position which would be occupied by a single latch, were such used.

In the application of the mechanism according to the present invention to the reversal of a printing press, it is obvious that the respective slide 35 or 36 can be satisfactorily engaged with the bed only at that 110 instant at which it is moving in the same direction as the bed, and at the same or approximately the same velocity as that of the bed, and, when a so-called reversing stud 39 is employed the velocity of the slide at such instants must be at its maximum. If 115 the reversing stud be dispensed with, the last-named restriction would not, however, arise, but the instant of engagement between the bed and slide must in that case be chosen so that the immediately subsequent 120

125

130

velocity of the slide does not increase. The precise conditions governing the relationship between the lengths of the connecting rod and crank radius necessary to satisfy 5 these requirements, will now be considered with reference at Fig. 2.

Let the crank pin 30 rotate with uniform angular velocity, and let V = the peripheral velocity of the crank pin, then, according to 10 a well known construction for obtaining the velocity of the slide 35, let the crank radius r of Fig. 2 represent to some scale the velocity V of the crank pin 30 and for any position of the crank pin let the line of the 15 connecting rod 31, produced if required as in Fig. 2, intersect the vertical through 1 (the axis of the bed motion shaft 1) at a point K, then the length 1K will represent the velocity of the slide 35 to the same scale as 20 that at which the radius r represents the velocity V of the crank pin 30. The velocity of the bed will be that of the pitch line of its driving pinion and whatever the crank radius r may be, since that radius is moving 25 with the same angular velocity as the bed driving pinion, at the position or instant of engagement between the slide 35 and the bed, the intercept 1K must be equal to the pitch line radius of the pinion.

30 The angular position of the crank pin 30 and the position of the slide 35 in which its velocity is a maximum can be determined by a tedious calculation, but a sufficiently close approximation is that which assumes 35 the velocity of the slide 35 to be at its maximum when the connecting rod 31 and crank radius r are at right angles with each other.

Let R = radius of pitch line of bed driving pinion,

40 Let a = angle of crank radius r with vertical line assumed passing through its axis of rotation, when retardation is to begin,

45 Let r = radius of crank arm,

50 Let e = horizontal distance of the slide 35 from the vertical line through the axis of rotation of the crank at the instant of engagement with the bed, being of any assumed length irrespective of half the travel of the bed at uniform velocity (indicated by the distance x in Fig. 2),

55 Let b = angle of connecting rod with horizontal line passing through axis of rotation of the crank, and

Let L = length of connecting rod 31.

Then, taking a case in which the bed driving pinion rotates through $260+2a$ degrees for the travel of the bed at uniform velocity, as in the original application, the distance apart of the two reversing latches = $2(x-e)$.

$$65 x = \pi R \left(\frac{130+a}{180} \right)$$

as in the last-mentioned application, but in the present case,

$$\tan b = \frac{R}{e} \text{ and not } \frac{R}{x},$$

and $\tan b$ therefore has a value other than

$$70 \frac{180}{\pi(180+a)}$$

Angle C = $(90-b)$, Angle D = $(90+b-a)$.

Also $R \sin C = r \sin D$, hence

$$r = \frac{R \sin C}{\sin D}$$

When $r=R$ then $C=D$ or $(90-b) = 80 (90+b-a)$, whence $a=2b$.

When $a=b$ the angle which the connecting rod 31 makes with the crank radius r will be a right angle and $r=R \cos a$ and

$$85 \tan b = \tan a = \frac{R}{e}$$

The last-named condition in which a is assumed to equal b , is that in which, as previously stated, the maximum velocity of the 90 slide 35 is equal to the normal or maximum velocity of the bed, and owing to the fact that when the velocity of the slide 35 is at its maximum, then its acceleration is zero, this condition is the best to employ. The 95 length L of the connecting rod 31 in any case is determined from the relation $L \sin b = r \cos a$, hence

$$100 L = \frac{r \cos a}{\sin b}$$

The basic principle of the bed-operating mechanisms constructed according to the present invention may be said to involve 105 a purely-rectilinear motion of varying velocity of a body such as a slide 35 produced through a connecting rod and rotating crank, and the utilization of such motion for effecting the reversal of motion of a rectilinearly reciprocating bed, within a period which is 110 less than one half of the period occupied by one rotation of the crank.

As hereinbefore mentioned, the present invention, besides being applicable to printing presses, is also applicable to other machines in which an organ is reciprocated similarly to the bed of a flat bed printing press, and for that reason it is to be understood that the word "bed" as used in this specification and claims, is intended, wherever the context admits of it, to include or apply to all of such organs.

Having described our invention, we declare that what we claim and desire to secure by Letters Patent is:—

1. In bed-reciprocating mechanism, the combination with a reciprocating bed and two co-axial spur pinions adapted to move it at uniform velocity in respectively opposite directions, of a crank adapted to rotate 125

130

- about the axis common to both pinions, two connecting rods, two slides each connected to the crank by one of the said rods and adapted to be reciprocated thereby at velocities 5 varying downwardly to and upwardly from zero, a two-member hook fast to each of the two slides, a stud rigid with the bed and adapted, by reason of the relative motion of the bed and slide, to engage with and disengage 10 from one member of each of the said hooks in alternation, two latches adapted to move independently of the bed but accompanying it throughout its travel, means adapted to automatically effect the engagement 15 of one of the said latches with and its disengagement from the other member of one of the said hooks near one end of the travel of the bed, and means adapted to automatically effect the engagement 20 of the other of the said latches with and its disengagement from the corresponding member of the other hook near the respectively opposite end of the travel of the bed, the respective engagements and disengagements of 25 the stud and latches with and from the hooks being effected at instants at which the velocity of the respective slide is equal or approximately equal to that of the bed, and within a period which is less than one half 30 of that occupied by one revolution of the crank.
2. In bed-reciprocating mechanism, the combination with a reciprocating bed and two spur pinions adapted to move the bed at uniform velocity in respectively opposite directions, of a crank adapted to rotate at the same angular velocity as the said pin- 35
- ions, two connecting rods, two slides each connected to the crank by one of the said rods and adapted to be reciprocated thereby at velocities varying downwardly to and upwardly from zero, a two-member hook fast to each of the two slides, a stud rigid with the bed and adapted, by reason of the relative motion of the bed and slide, to engage with and disengage from one member of each of the said hooks in alternation, two latches adapted to move independently of the bed but accompanying it throughout its travel, means adapted to automatically effect the engagement of one of said latches with and its disengagement from the other member of one of the said hooks near one end of the travel of the bed, and means adapted to automatically effect the engagement of the other of the said latches with and its disengagement from the corresponding member of the other hook near the respectively opposite end of the travel of the bed, the respective engagements and disengagements of the stud and latches with and from the hooks being effected at instants at which the velocity of the respective slide is equal or approximately equal to that of the bed and within a period which is less than one half of that occupied by one revolution of the crank. 40
